LIPSTICK CASE

Albert Gelardin, New York, N. Y.

Application May 3, 1947, Serial No. 745,701

17 Claims. (Cl. 206—56)

1

This invention relates to improvements in lipstick cases, and, more particularly, to novel propellor cases embodying coil compression springs contained in and actuated by a rotatable base member.

In my prior application Serial No. 625,801, filed October 31, 1945, I disclosed and claimed a lipstick case consisting of an outer shell with a rotatable base attached thereto, the shell having a cage or fenestrated retaining device fitted therein to serve as a retainer for a coil compression spring, to the free end of which a cup is attached, the cup receiving a lipstick, and movable in the shell by the spring. In this form, the cup rotates with the spring as the latter is actuated by the rotatable base. Under such conditions, the form of the cup and of the lipstick carried therein is essentially restricted to a circular or cylindrical type.

I have now found that lipstick cases of the compression spring actuated type can be utilized in cross-sectional shapes of any desired contour, and so constituted and arranged that the lipstick cups are prevented from rotation, yet are freely movable along the longitudinal axis of the device.

The improvements of the present invention will be more clearly understood by reference to the accompanying drawings, in which certain preferred embodiments are shown, by way of illustration only, as it is not intended to be limited to the forms here shown, except as such limitations are clearly imposed by the appended claims.

In the drawings like numerals refer to similar parts throughout the several views, of which

Fig. 1 is an elevation of a lipstick case of circular cross section;

Fig. 2 is a vertical section, taken on line 2—2 of Fig. 1;

Figs. 3 and 4 are horizontal sections taken on lines 3—3 and 4—4 of Fig. 2;

Figs. 5 and 6 are views similar to Figs. 1 and 2, showing vertical ridges comprised of raised dots;

Figs. 7 and 8 are a side elevation and an end elevation of a curvilinear tear-drop shaped case;

Fig. 9 is a top plan view; and

Fig. 10 is a bottom plan view of the lipstick case shown in Figs. 7 and 8;

Fig. 11 is a transverse vertical section taken on the major axis of Figs. 7 and 8;

Fig. 12 is a vertical section taken on line 12—12 of Fig. 11, and

Figs. 13 and 14 are horizontal cross sections taken on lines 13—13, 14—14 of Fig. 11.

2

The lipstick cases of the present invention consist essentially of an outer, curvilinear shell with a rotatable base attached thereto, the rotatable base having a depression therein or forming a well to receive a substantial portion of a coiled compression spring. A barrier is included in the hollow base at an appreciable distance from the bottom, and of such dimensions, and so oriented, that the helical turns of the spring will have normal bearing engagement against the barrier and yet can thread their way past the barrier without distortion or binding. The bottom of the spring is preferably loosely disposed within the base and is so configured that the lower end of the spring cannot thread its way past the barrier. The upper end of the spring is attached to a lipstick cup which is slidably mounted within the shell, the cup being so mounted within the shell that it cannot rotate. The non-rotatability of the cup is assured by the particular shape of the shell and of the cup where they are both curvilinear but non-cylindrical, and, when cylindrical, by providing grooves or other means in the shell and the cup for mutual engagement. For cylindrical members an extra sleeve, having a radial slot engageable by a stud or protuberance on the cup, may also be used to assure the desired slidability and non-rotation thereof.

In operation, the lipstick case will be actuated by rotating the base, which during its rotation collects or releases a certain amount of the coiled spring from the cavity within the base, thereby causing the cup to rise or descend within the shell or casing.

The lipstick cases herein are characterized by (1) simplicity of parts; (2) simplicity of assembly; (3) unusual shaped pieces of cosmetic which are more suitable for application to the lips.

Where unusual shapes of lipsticks are used, the swivel type cases herein will elevate and lower the lipstick mass without rotating the same in its longitudinal reciprocating travel. As will be shown more in detail herein and in divisional application, Serial No. 54,625, cosmetics or lipstick masses can be made in tear-drop cross-section, diamond cross-section, and square cross-section, so that as they are used, there will always be a point or edge available for application to the lips to permit the forming of a sharply delineated line on the lips.

Another and important advantage of the devices herein, and particularly with reference to the non-circular, curvilinear containers, resides

in the fact that the shape of the container permits the base to be snapped into place with great ease. An additional advantage of the cup-base construction resides in the fact that all the spring pressure, when the spring is compacted below the barrier pin, does not tend to push the base away from the sleeve. Furthermore, in the present case, the free swiveling of the base acts to let the spring compress and decompress without distortion.

Considering the individual structures more in detail, the form illustrated in Figs. 1 to 4 will be considered first. According to this form of the invention the lipstick case comprises a curvilinear shell or case 10, a rotatable base or cap 20, a cup 30, and a spring 40.

The shell or casing 10 comprises a generally cylindrical body portion 11 of circular cross-section, a domed or peened over top 12 defining an aperture 13, a bottom 14, and a horizontal groove 15 adjacent the bottom and parallel therewith and defining an internal ridge 16. While the groove 15 is shown as continuous, a row of spaced indentations or depressions can be used, in which case the ridge 16 would be comprised of spaced, embossed or raised dots. A vertical groove 17, or row of indentations 17', severally defining an internal longitudinal ridge 18, or row of raised dots 18', is formed along one side of the casing.

The base 20 comprises a generally cylindrical body portion 21 having a flat base 22 with a shouldered flange extension 23. A groove 24 is formed in the outer surface of section 21 and adjacent the shouldered flange 23. The collar or body portion 21 and the flat base 22 define a central space or cup 25 into which is freely received the bottom compressed portion 41 of spring 40. A barrier pin 26 is fitted in a diameter of the body 21, and oriented at such an angle as to equal one-half of the pitch of the unexpanded or free turns 42 of the spring. At its upper end 43 the spring is secured to cup 30 by means of a hollow rivet 44. The free end 45 of the spring may be bent as shown to insure its engagement and retention by the barrier pin 26 when the spring is rotated to its full expanded length. Normally, the full, expanded length of the spring will exceed the over-all length of the casing 10, so as to insure that the tip of the lipstick carrier or cup 30 will project through the open mouth or aperture 13 of the casing.

Referring now to the carrier 30, this will be seen to comprise a cup-shaped member having a wall portion 31, a base 32 apertured to receive securing rivet 44, and provided with spacing knobs or ridges 33. The cup may be provided further with a pair of spacers or ridges 34 which are adapted to engage the ridge 18 formed on the inside of the casing by the groove 17, the inter-engagement of the ridge 18 and beads 34 serving to prevent the cup 30 from rotating in the casing 10, yet permitting its free movement in and along the casing in either direction. The cup 30 is adapted to extend beyond the lip or opening 13 to permit full access to the lipstick mass 50, which is contained therein, and to permit the ready removal of the lipstick stub and the insertion of a fresh lipstick mass.

In the form shown in Figs. 1 to 4, the rotatable member or cap 20 has been shown with a solid bottom 22. In the forms shown in Figs. 7 to 14, the base or rotatable member 20 is bottomless and forms, essentially, a continuous cylinder 21 having a flanged or knurled knob 23'. As shown in Figs. 11 and 12, the inner wall of the cylinder 21

may be provided with a helical groove 27 comprising one or more turns, the pitch of the groove being equal to the free pitch of the expanded spring. Where the rotating member is provided with a helical groove, the barrier pin 26 will be dispensed with.

Considering the form illustrated in Figs. 7 to 14, a tubular casing 70, of curvilinear, ovoidal cross-section, has a major circular edge or wall section 71, an axially opposed circular section 72, and convergent sides 73, 74. The tubular casing is provided with the usual domed or peened end 75, defining an aperture to receive a conformed lipstick holder or cup 30b having the spaced horizontal ridges 33b therearound secured to or formed as part of the wall section 31b. The base of the cup 32b is secured to the compression spring 40 in the usual manner by hollow rivet 44. A base or cover plate 76 of generally ovoidal shape is provided with studs or upstanding portions 77, 78 at the ends of the major axis, and these studs are fitted into skirts 71a, 72a formed at the bottom of the casing 70, the parts being secured by the usual pins 68. The lipstick mass 79 is of tear-drop shape, as shown, and this shape insures a linear edge at all times, together with flat or round application surfaces to permit the application or formation of any desired contour of lipstick rouge to the lips.

It will now be appreciated that there has been provided novel lipstick cases of the propell-repel type which are adapted to use lipstick masses of varying cross-section, yet which use controlling or operating mechanism of uniform structure and mounting and which permit the variation of casing parts and lipstick carriers without requiring any fundamental variation in the operating mechanism. It will also be appreciated that there has been provided a novel lipstick case and operating mechanism which is spring-driven, yet in which the spring is never exposed to conditions tending to bind or cause the same to jam so that the spring, being freely rotatable in the casing, under operating conditions, will not twist or become distorted and break during use.

What is claimed is:

1. A lipstick holder comprising a tubular casing, a rotatable base, a non-rotatable lipstick carrier mounted for reciprocation in the casing, a compressible spring reciprocable with and fixed to the carrier and nested in the rotatable base, and restraining means for the spring in the base and maintaining the subjacent spring in compressed condition.
2. Rotatable base according to claim 1 in which the member is cup-shaped.
3. Rotatable base member according to claim 1 which is an open-ended cylinder.
4. Base member construction according to claim 3 in which the bottom of the open cylinder is closed by a plate secured to the bottom of the casing.
5. Base member according to claim 1 in which restraining means for the spring comprises a barrier pin.
6. Base member according to claim 1 in which the restraining means for the spring comprises a helical groove.
7. Base member according to claim 1 in which the restraining means comprises a barrier pin mounted transversely of the open end of the base.
8. Barrier pin according to claim 7, in which the pin is mounted at substantially one-half the free pitch angle of the spring.
9. Base member according to claim 1, in which

the spring is held compressed beneath the restraining means and freely expanded between the said restraining means and the carrier.

10. A lipstick holder according to claim 1, in which the casing is curvilinear in cross-section.

11. A lipstick holder according to claim 1, in which the casing is circular in cross-section.

12. A lipstick holder according to claim 1 in which the tubular casing is tear-drop in cross-section.

13. A lipstick holder according to claim 1 in which the casing is circular and is provided with an internal vertical ridge and the lipstick carrier is provided with spaced vertical ridges engaging the casing ridge.

14. Lipstick holder according to claim 13 in which the said ridges are severally comprised of lines of raised dots.

15. Lipstick holder according to claim 1, in which the rotatable base is cup-shaped and freely receives the bottom of the compressed spring, and the base and the casing have interlocking tongue and groove snap engagement.

16. In a lipstick holder comprising a tubular casing, a rotatable base, a non-rotatable lipstick carrier conformed to and mounted for reciprocation in the casing, a compressible spring fixed to the carrier and nested in the rotatable base, and restraining means for the spring formed in the base and maintaining the subjacent spring in compressed condition, the improvements comprising a tear-drop casing, a rotatable base being an open-ended cylinder with an exposed actuating flange, a cover plate over the flanged end of the base and secured to the casing, and a helical groove in the top portion of the base comprising a complete turn conforming to the pitch angle of the freely expanded spring and maintaining

the subjacent coils of the spring under compression.

17. In a lipstick holder comprising a tubular casing, a rotatable base, a non-rotatable lipstick carrier conformed to and mounted for reciprocation in the casing, a compressible spring fixed to the carrier and nested in the rotatable base, and restraining means for the spring formed in the base and maintaining the subjacent spring in

18. compressed condition, the improvements comprising a tear-drop casing, a rotatable base being an open-ended cylinder with an exposed actuating flange, a cover plate over the flanged end of the base and secured to the casing, and a barrier pin in the top portion of the base and transversely thereof and at an angle equal to one-half the free pitch angle of the spring and maintaining the subjacent coils of the spring under compression.
